CLAIM

The ornamental design for a LED lamp module, as shown and described.

DESCRIPTION

FIG. 1 is a perspective view of a LED lamp module showing my/our new design;

FIG. 2 is a front elevational view thereof, the rear side being a mirror image;

FIG. 3 is a left side elevational view thereof;

FIG. 4 is a right side elevational view thereof;

FIG. 5 is a top plan view thereof;

FIG. 6 is a bottom plan view thereof;

FIG. 7 is an alternate perspective view, as seen from the bottom; and,

FIG. 8 is a reference view similar to FIG. 1, showing the LED lamp module in use with the light emitting part hatched with diagonal lines.
